UNITED STATES PATENT OFFICE.

LEON GNIEWCRYŃSKI, OF BROOKLYN, NEW YORK.

WRENCH.

1,245,581.

Specification of Letters Patent.

Patented Nov. 6, 1917.

Application filed April 26, 1917. Serial No. 164,669.

To all whom it may concern:

Be it known that I, LEON GNIEWCRYŃSKI, a subject of the Emperor of Austria, resident of Brooklyn, county of Kings, and State of New York, have invented certain new and useful Improvements in Wrenches, of which the following is a specification.

This invention relates to improvements in wrenches, and has as its special object the provision of a wrench in which the movable jaw is rapidly movable with relation to the fixed jaw and which is readily relieved from its control means.

A further object is to provide means of relatively thin construction, without having parts projecting from the side which might interfere with its usual operation, the wrench being essentially heavy and strong.

These and other like objects are attained by the novel design, construction and combination of parts hereafter described and shown in the accompanying drawings, forming a material part of this disclosure, and in which:—

25 Figure 1 is a side elevational view of a wrench made in accordance with the invention.

Fig. 2 is a similar view of the same, one of the cover blades being removed.

30 Fig. 3 is a view similar to Fig. 2 showing the parts in a released position.

Fig. 4 is an edge view of the wrench as shown in Fig. 1.

Fig. 5 is a transverse sectional view taken 35 on line 5—5 of Fig. 3.

Fig. 6 is a fragmental view of the wrench looking from line 6—6 of Fig. 3.

Fig. 7 is a sectional view taken on line 7—7 of Fig. 6, and

40 Fig. 8 is a perspective view showing a screw-driver as attached at the opposite end of the wrench.

Formed with the body handle 10 are raised edges 11 and 12, respectively on the 45 front and back of the implement, the same having recesses 13 and 14 suited to receive corresponding projections 15 and 16 formed with the cover plate 17, which is held to the body handle by means of screws 18.

50 The head end of the wrench is materially thickened along both edges terminating in a fixed jaw 22 from which extends a diagonal bar 23, through which is formed a longitudinal slot 24, in which is slidably engaged the reduced shank 25 of the movable jaw 26, the shank 25 having inserted in it a rigid

pin 27 having a flattened portion engageable against the lower or inner side of the bar 23, thereby holding the jaw in permanent engagement but permitting the same to slide freely along the bar, a recess 28 being provided in the body portion of the wrench in which the pin may operate.

The movable jaw 26 is pressed away from the fixed jaw 22 by means of the flat spring 32 held in the interior of the wrench handle by the screw 33 so as to normally present an opening between the jaws.

A sliding bar 38 is provided with an operating projection 39 and has an angular 70 head 40 adapted to engage against the outer side of the shank 25 which obviously is caused to traverse the bar 23 within the slot 24 when the bar 38 is advanced toward the operative end of the implement.

This bar is normally held in position by means of the hollow handle 10 by fixed pins 42 and 43 on one side and the raised edges 12 upon the other.

Formed within the inner edges of the bar 80 38 are a plurality of ratchet teeth 44, similar teeth being formed upon a lever 45 pivoted upon the shank of the screw 18 within the hollow body of the implement, and having a reduced extension 46 formed in the 85 opposite end, the outer end of which rests against the outermost pin 43, the lever being normally pressed forward so as to cause engagement of the teeth by means of the flat spring 47 secured by the screw 33.

In order to release the bar 38 so that it may be moved rearwardly, thereby permitting the jaw 26 to be retracted, a knob 48 having a stem 49 passes transversely through the bar 38 and is provided with a fixed 95 collar whereby it is prevented from passing outward and hence from loss, the point of the rod 49 being adapted to engage against the inner side of the extension 46 of the lever 45 by means of which it can 100 be pressed back, overcoming the tension of the spring 47, and releasing the rod 38 which is moved back under pressure of the spring 32 when the jaws are opened.

In operation, when it is desired to close 105 the jaws, as upon an object to be turned, pressure is merely applied to the projection or plate 39, advancing the bar 38 toward the head of the implement and causing the jaw 26 to move in the direction of the fixed 110 jaw 22.

When a sufficient movement has been

transmitted, the teeth 44 on the element engage with the teeth on the lever 45, holding the bar 38 rigidly outward, and by means of the angular spear-shaped head 40, holding the jaw 26 in its adjusted position.

When it is desired to release the jaw, pressure is applied upon the knob 48, which moves away the lever 45, overcoming the tension of the spring 47 and releasing the 10 engagement of the ratchet teeth, permitting the bar 38 to be moved toward the rear or lower end of the handle, the jaw 26 being caused to follow the bar under action of the spring 32.

15 The opposite end of the implement may be used as a screw-driver, inserted nibs 50 being receivable between fixed lugs 52 formed with the lower side 10 of the handle, the same having ends of various sizes, as 53 20 and 54, either of which may be held in an operative position through the slot 55, with which is engaged a dog 56 held normally within the slot by the spring 57 and operable by the extending lever 58.

25 From the foregoing, it will be seen that a neat and serviceable implement of pleasing appearance has been described and which can be operated as an angle wrench from either side in an obvious manner.

30 Having thus described my invention, what I claim as new, and desire to secure by Letters Patent, is:—

1. In a wrench of the class described, the combination with a hollow body, a handle affixed thereto, an integrally formed head, and a fixed jaw formed in said head, of a 35 jaw slidably within said head, means for normally keeping said jaw in an open position, a bar slidably engaged within said 40 handle, said bar having an angular head engageable with said movable jaw, a plurality of ratchet teeth formed on one side of said bar, a lever fulcrumed in said cas-

ing having teeth normally engaged with said ratchet teeth, means for advancing said 45 bar toward said head, and means for depressing said lever whereby said teeth may be disengaged.

2. In a wrench, the combination with a hollow handle and a body, of a slotted head 50 integrally formed therewith, a jaw formed with said slotted head, a spring adapted to press said movable jaw away from said head, a bar slidably engaged within said head and body, said bar having an end contactable with said movable jaw, a plurality of ratchet teeth formed with the inner side 55 of said slideable bar, a lever fulcrumed in said casing, said lever having a plurality of teeth engageable with the ratchet teeth 60 upon said slideable bar, means for maintaining said lever and bar in relative position, a spring adapted to move said lever teeth into engagement with the teeth on said bar, means for moving said bar toward said movable jaw, and means for releasing said lever teeth from the ratchet teeth on said bar. 65

3. In a wrench, the combination with a hollow casing and a cover therefor, of a head formed at one end of said casing, said 70 head having a longitudinal slot, a fixed jaw formed with said head, a movable jaw operable within the slot in said head, means for engaging said movable jaw therein, a ratchet bar movable longitudinally within said casing, a head formed therewith adapted to engage with said movable jaw, means for operating said sliding bar, means for holding said sliding bar in operative position, means for engaging said sliding bar in an 75 adjusted position, and means for disengaging said engaging means. 80

In testimony whereof I have affixed my signature.

LEON GNIEWCRYŃSKI.
